UNITED STATES PATENT OFFICE.

JAMES M. KYLE, OF SPOKANE, WASHINGTON, ASSIGNOR TO SMITH-UPTON CO., OF SPOKANE, WASHINGTON, A CORPORATION OF WASHINGTON.

BALL-THROWING MACHINE.

Specification of Letters Patent. Patented Sept. 12, 1916.

1,109,123.

Application filed December 30, 1913. Serial No. 68,430.

It may be noted

Be it known that JAMES M. KYLE, a citizen of the United States, residing at Spokane, in the county of Spokane and State of Washington, have invented certain new and useful Improvements in Ball-throwing Machines, of which the following is a specification.

The present invention has relation to mechanical projecting devices of the type designed for throwing balls or similar objects.

As a standard throwing machine the invention may be used for amusement apparatus, as for example tennis games, or even the playing out of a game similar to that India plays from the condition the release and flight of each ball being controlled by a particular mechanism forming the essential feature of the present improvement. The invention, however, is susceptible of use as a device for use for the projection of objects from throwing or projecting machines, of various types, and will be explained more fully upon a complete understanding of the following description, obtainable by means of the following detailed description and the accompanying drawings to which:

Figure 1 is a front view of a projecting machine embodying the essential features of the invention. Fig. 2 is a side view showing more particularly the throwing arm and associated controlling mechanism. Fig. 3 is a plan view of the means shown in Fig. 2. Fig. 4 is a fragmentary side view of the setting device. Fig. 5 is an enlarged detail view showing more particularly the ball release device. Fig. 6 is an enlarged view of the controlling arm partly broken away and shown in section to bring out the mounting of the release finger and release locking catch. Fig. 7 is a detail perspective view of the controlling disk.

In a machine of the type to which the improvements of this invention are particularly applicable there is provided a suitable supporting stand A upon the upper portion of which is a rotatable throwing or projecting device B supported on a shaft C adapted to be driven at high speed by connection with any suitable type of motor D. Within the purview of the invention the above instrumentalities may be of any conventional construction, generally speaking, and the controlling mechanism now to be set forth is

associated primarily with the throwing device B.

The throwing device B consists of a hollow arm which being fixed to the shaft C rotates with said shaft, the arm having the delivery portion 1 and the main hollow body portion 2. The body portion 2 of the throwing arm will preferably be provided at one side thereof and substantially at its axis with a receiving opening adapted to receive balls or other similar objects from a delivery chute 3 suitably supported at one side of the machine. The balls will be delivered from the chute 3 into the throwing device B under the control of any suitable cut-off or regulating instrumentalities, same not being shown owing to the fact that they are not material to the improvements forming the basis of this invention. It suffices to state, therefore, that when the objects to be projected are received by the throwing device B, owing to the peculiar hollow formation of the latter, through centrifugal action said objects will pass into the delivery portion 1 of the device B. The means to control not only the release of the objects projected by the device B, but the time when such release takes place, constitutes the present invention. The time of release of the ball or other object to be projected from the device B necessarily determines the direction of flight of the ball, such direction being variable by the instrumentalities now to be set forth so that the ball may be thrown to obtain variable flights or paths of movement of the projected object, whereby what are ordinarily characterized as high or low balls, or balls operating in paths intermediate the high and low maximum movements capable of being imparted to the object, may be produced.

As seen best in Fig. 2, there is mounted on the device B a curved frame 4 intermediate the ends of which is pivotally supported at 5 the controlling member 6. The controlling member 6, as seen best in Fig. 6, carries at its outer end a detent 7 adapted to be locked in substantial alinement with the member 6 by the bell crank catch 8, one arm of which is opposite an opening 6' near the outer extremity of the member 6.

The outer portion of the controlling member 6 is adapted to operate in a slot provided lengthwise of the delivery portion 1 of the throwing device B, this arrangement

- permitting the detent 7 to engage and detain within said delivery portion 1 a ball supplied to the throwing device to be projected thereby. In other words the detent 7 constitutes an obstruction movable in the throwing device and said detent must be released in order to release the ball or other object to be projected in the operation of the machine.
- 10 The controlling member 6 at its inner end is weighted as seen at 6" so that as the throwing device B rotates normally, when not supplied with a ball to be projected the centrifugal action of the weight part 6" is such as to maintain the controlling member 6 in the position shown in dotted lines in Fig. 2, or with its weighted end inclining outwardly in respect to the axis of the device B. A dash-pot 9 secured in any suitable way to the body portion 2 of the device B is connected with the weighted end 6" of the controlling member 6 by means of a rod 10 and forms a governor for the movement of the member 6.
- 15 On the side of the throwing device B adjacent to the point of connection of the shaft C therewith is provided a journal 11 which supports a sleeve 12 thereon in such a manner as to permit movement of the sleeve longitudinally of the journal. The sleeve is formed with an arm 13 connected by a rod 14 with an arm 15 on a shaft 16 carried by the outermost portion of the frame 4, said shaft 16 having fixed thereto a curved release member 17 the free end of which is adapted to operate through the opening 6' of the controlling member 6 so as to tap or engage the locking catch 8 in such a manner as to trip said catch out of engagement with the detent 7 whereby a ball held by said detent against release from the throwing device, will be released and projected by the latter. The means to act upon the parts just mentioned so as to effect 40 and time the release action of the detent 7 includes a releasing disk 18 loosely mounted on the shaft C and shiftable thereon by means of a suitable operating rod 19 leading to a lever or other manually controllable device. The disk 18 is formed with a cam 18' on its periphery which cam is adapted to cooperate with a roller 20 supported by another arm 21 which projects from the sleeve 12 in the direction opposite the arm 13.
- 45 The coöperation between the roller 20 and the cam 18' is governed by the position of the sleeve 12 on the journal 11 and it is contemplated to shift said sleeve so that during rotation of the device B the members 20 and 18' will not coact, other movement of the sleeve being adapted to place said members in coöperation so that the release of the ball or object to be projected may then be effected.

The movement of the sleeve 12 is governed by a setting device adapted to be controlled by the controlling member 6 and seen best in Figs. 2 and 4. This setting device consists of a lever 22 pivoted to a bracket 23 projecting from a side of the device B, one arm of the lever 22 being attached to an actuating rod 24 the outer end of which rod operates through a guide opening 25 in the frame 4 and is adapted to be impinged by the inner or weighted end portion 6" of the controlling member 6. The lever 22 has a yieldable or spring arm 22^a the outer end of which engages in a notch 12' formed in a side of the sleeve 12 and by movement of the lever as hereinafter described the sleeve 12 is adapted to be shifted inwardly and outwardly on the journal 11 whereby the roller 20 may operate on the circular periphery of the disk 18 without release of the detent 7, or may be moved to that portion of the periphery of said disk having the cam 18' so that the latter may actuate the release device comprised by the parts 12, 13 and 21 and thereby effect release of the detent 7 so that the ball or object may be projected by the device B. There is provided a U-shaped engaging member 26 detachably and adjustably supported on the outer end of the delivery portion 1 of the throwing device B, opposite the detent 7, which coöperates in the delivery of the ball from the member 1 upon release of the detent.

The details of construction of the invention having been explained, the operation of the machine will be set forth.

Operation: Fig. 2 of the drawings illustrates the parts in the positions assumed thereby just as the ball 27 has been released from the throwing device B in the projecting operation. As the ball enters the device B the rotation of the latter and centrifugal action causes said ball to pass to the delivery portion 1 where it engages with the controlling member 6 which at such time is in the dotted line position shown in Fig. 2. The weight of the ball acting upon the controlling member 6 carries the latter outward to the full line position shown in Fig. 2, overcoming the action of the weighted end 6" of said member 6 in holding said member in said dotted line position. The movement of the ball to the outer extremity of the delivery member 1 is retarded by the dash-pot 9 co-operating with the member 6. When the ball reaches the delivery point of the member B it is detained from being projected by means of the detent 7 but at approximately the same time as the latter coöperates with the ball the controlling member 6 at its weighted end engages the actuating rod 24 of the setting device, tilts the lever 22 and moves the spring arm 22^a outward to shift the sleeve 12 so as to cause the roller 20 to be

aligned with the peripheral portion of the disk 18 having thereon the cam 18'. The release device is now set in operative position to release the ball 27 from the detent 7, 5 the release being actually effected by the partial rotation of the sleeve 12 of said release device incident to engagement of the cam 18' and roller 20, the resultant action being an inward pull on the rod 14 causing 10 the release member 17 to impinge the adjacent arm of the catch 8 and trip said catch out of engagement with the detent 7, freeing the ball 27 for its projecting movement. The operator controlling the movement of the 15 rod 19 and thereby the disk 18 may readily shift the disk so as to vary the time when the cam 18' coacts with the roller 20 and in this manner the flight of the ball as to height is manually governed. As soon as 20 the weight of the ball is removed from the controlling member 6 upon release of the detent 7 it will be obvious that the weighted end of the member 6 will carry said member back to its dotted line position in Fig. 2 and 25 the centrifugal action of the rod 24 will pull the spring arm 22* back toward the portion 2 of the throwing device B and thereby shift the sleeve 12 to its normal position wherein the roller 20 is not coöperative with the cam 30 18'. It is to be further understood that the operativeness of the release device including the parts 12, 13, 14, 17 and 20 is governed by the setting device, the latter in turn being governed by the movement of the ball itself. 35 On the peripheral portion of the disk 18 the latter is supplied with a stop flange 28 adapted to coact with a projection 29 on the arm 21 to avoid liability of outward shifting movement of the member 12 when the 40 roller 20 is just opposite the cam. The restoration of the detent 7 to its locked position in relation to the catch 8 is effected automatically by means of engagement of the inner end of the detent with a cushion- 45 ing abutment 30, the latter being located at the inner end of a slot formed in the delivery portion 1 of the throwing device B. The release detent 7 coacts with the abutment 30 as the controlling member 6 returns to its 50 dotted line position in Fig. 2.

Having thus described the invention, what is claimed is:

1. In a projecting machine, the combination of a throwing device comprising a delivery portion, a detent carried by the latter, locking means for said detent, an automatically operating controlling member coöperative with said detent to render the lock means coöperative therewith, and manually controlled means for effecting release of the detent to permit projection of an object restrained thereby.

2. In a projecting machine, the combination of a throwing device comprising a delivery portion, a detent carried by the latter,

locking means for said detent, a centrifugally operating controlling member coöperative with said detent to render the lock means coöperative therewith, and manually controlled means for effecting release of the 70 detent to permit projection of an object restrained thereby.

3. In a projecting machine, the combination of a throwing device comprising a delivery portion, a detent carried by the latter, 75 locking means for said detent, an automatically operating controlling member coöperative with said detent to render the lock means coöperative therewith, manually controlled means for effecting release of the 80 detent to permit projection of an object restrained thereby and comprising normally inoperative release parts, and means adapted to be acted on by the said controlling member for setting the release parts in an opera- 85 tive position.

4. In a projecting machine, the combination of a throwing device comprising a delivery portion, a detent carried by the latter, locking means for said detent, a centrifugally operating controlling member coöperative with said detent to render the lock means coöperative therewith, manually adjustable means for effecting release of the 90 detent to permit projection of an object restrained thereby and comprising normally inoperative release parts, and centrifugal means adapted to be acted on by the said controlling member for setting the release parts in an operative position. 95

5. In a projecting machine, the combination of a throwing device comprising a delivery portion, a detent carried by the latter, locking means for said detent, a centrifugally operating controlling member coöperative with said detent to render the lock means coöperative therewith, manually controlled means for effecting release of the 100 detent to permit projection of an object restrained thereby, an operative connection between the detent and said controlling member, and a retarding device connected with the controlling member to govern the centrifugal movement of the same. 105

6. In a projecting machine of the class 115 described, the combination of a throwing device including a delivery portion, a detent for restraining the object to be delivered, a controlling member mounted upon said throwing device and carrying said detent and comprising means acting centrifugally to hold the detent in the path of movement of the object to be projected, normally inoperative manually adjustable release mechanism associated with said detent, and means operable by said controlling member to render the manually adjustable means aforesaid operative to release the detent. 120

7. In a projecting machine of the class 130

- described, the combination of a rotative throwing device, a ball restraining detent thereon, a controlling member for said detent adapted to be operated by the object to be projected from the throwing device, and manually controllable operating means for releasing the detent to effect projecting action of the throwing device, and means operable by said controlling member for governing the action of said manual means.
8. In a projecting machine of the class described, the combination of a rotative throwing device, a ball restraining detent mounted thereon, a controlling member movable on said device and carrying said detent and adapted to be operated by movement of the object to be projected by the throwing device, means for retarding the movement of the controlling member by such object, means for releasing the detent, and means intermediate the controlling member and the releasing means to govern the action of the latter.
9. In a projecting machine of the class described, the combination of a throwing device, a detent mounted thereon for restraining the object to be projected by such throwing device, lock means for said detent to hold it in restraining position, means for releasing the detent from said locking means, and a controlling member operable by the object to be projected by the throwing device and coacting with said release means whereby to govern the action of the latter.
10. In a projecting machine of the class described, the combination of a rotative throwing device having a delivery portion, a detent for restraining the object to be projected from said delivery portion, a controlling member carrying said detent and mounted upon said throwing device, said controlling member including centrifugally acting means to maintain the detent in the path of movement of the object to be projected by the throwing device, manually controlled release mechanism comprising normally inoperative release parts, and setting means intermediate said controlling member and the normally inoperative release parts to render the latter operative.
11. In a projecting machine of the class described, the combination of a rotative throwing device having a delivery portion, a detent for restraining the object to be projected from said delivery portion, a controlling member carrying said detent and mounted upon said throwing device, said controlling member including centrifugally acting means to maintain the detent in the path of movement of the object to be projected by the throwing device, manually controlled release mechanism comprising normally inoperative release parts, and setting means intermediate said controlling member and said release parts including a centrifugally acting device operable by the controlling member to render the inoperative release parts operative, and operable centrifugally to restore said inoperative release parts to normal positions.
12. In a projecting machine of the class described, the combination of a rotative throwing device having a delivery portion, a detent for restraining the object to be projected from said delivery portion, a controlling member carrying said detent and mounted upon said throwing device, said controlling member including centrifugally acting means to maintain the detent in the path of movement of the object to be projected by the throwing device, a locking device for said detent, manually controlled release mechanism coacting with the locking device to operate the detent to release the object retained thereby, and release mechanism for said locking device including a releasing arm, a shiftable member normally out of coöperative relation with said arm, and means for adjusting the position of said shiftable member to vary its time of coaction with respect to the arm and correspondingly vary the time of release of the detent.
13. In a projecting machine of the class described, the combination of a rotative throwing device having a delivery portion, a detent for restraining the object to be projected from said delivery portion, a controlling member carrying said detent and mounted upon said throwing device, said controlling member including centrifugally acting means to maintain the detent in the path of movement of the object to be projected by the throwing device, and release mechanism for said detent including an adjustable part, release devices coöperative with said adjustable part and normally maintained in an inactive position relative thereto, and setting means including an actuating rod operable by the controlling member for shifting said release parts into operative relation in respect to the adjustable part aforesaid.
14. In a projecting machine of the class described, the combination of a rotative throwing device having a delivery portion, a detent for restraining the object to be projected from said delivery portion, a controlling member carrying said detent and mounted upon said throwing device, said controlling member including centrifugally acting means to maintain the detent in the path of movement of the object to be projected by the throwing device, a manually controlled release mechanism including a release member for the detent, actuating means for said release member including a rod, a sleeve connected with said rod, an arm projecting from said sleeve, a cam device

coacting with said arm, and setting means operable by the controlling member for shifting said arm into and out of active relation in respect to the cam device.

- 5 15. In a projecting machine of the class described, the combination of a throwing device, a controlling member pivoted thereto, an object restraining detent carried by said controlling member, a locking catch for said detent, the controlling member including centrifugally acting means for holding said member in a position to be actuated by the object to be projected, means to retard the movement of the controlling member when operated by the object to be projected, a release mechanism including a normally inoperative release device, a manually controlled part for actuating said release device, and setting means intermediate the said pivoted controlling member and the release device for shifting the latter to a position for co-operation with said manually controlled part.
- 20 16. In a projecting machine of the class described, the combination of a throwing device, a controlling member pivoted thereto, an object restraining detent carried by said controlling member, a locking catch for said detent, the controlling member including centrifugally acting means for holding said member in a position to be actuated by the object to be projected, means to retard the movement of the controlling member when operated by the object to be projected, release mechanism including a normally inoperative release device, a manually controlled part for actuating said release device, and setting means intermediate the said pivoted controlling member and the release device for shifting the latter to a position for co-operation with said manually controlled part, said setting device consisting of a lever having a yieldable arm engaging said release device for causing its shifting movement and a centrifugally acting rod connected with said lever to restore the release device to normal position and adapted to be forcibly operated by the controlling member in order to shift the release device for coaction with the manually controlled part.
- 25 17. In a projecting machine of the class described, the combination of a throwing device, an object restraining detent mounted

thereon, lock means for said detent, manually controlled release means for said lock means, and a controlling member automatically operable after release of the detent to restore the co-operation of the lock means therewith.

18. In a projecting machine of the class described, the combination of a throwing device, an object restraining detent mounted thereon, lock means for said detent, manually controlled release means for said lock means, an abutment for co-operation with the detent, and a controlling member movably mounted upon the throwing device and carrying said detent and lock means, said controlling member including centrifugally acting means to cause co-operation of said detent with said abutment to restore the co-operation of the lock means and detent means.

19. In a projecting machine, the combination with a projecting arm and operating means therefor, of detent means co-operative with said arm for detaining an object from being projected, and means for controlling the action of said detent means operable by movement of the object to be projected.

20. In a projecting machine, the combination with a projecting arm and operating means therefor, of detent means on the arm for detaining the object to be projected from being delivered, normally inoperative controlling means for said detent means, and means operable by movement upon the arm of the object to be projected whereby to render said controlling means operative at a predetermined time.

21. In a projecting machine, the combination of a hollow throwing arm and operating means therefor, detent means on said arm for restraining against delivery the object to be projected, controlling means for effecting the release of said detent means to permit delivery of the object to be projected, said controlling means being normally inoperative, and means adapted to be actuated by movement in the hollow portion of said arm of the object to be projected, whereby to render the controlling means operative at a predetermined time for effecting release action of the detent aforesaid.

In testimony whereof I affix my signature. 125
JAMES M. KYLE.
